UNITED STATES PATENT OFFICE

CARL GRETER, OF BERLIN-SCHONEBERG, GERMANY

ELECTRIC SWITCH

Application filed October 29, 1928, Serial No. 315,783, and in Germany April 17, 1928. Renewed September 19, 1931.

This invention comprises improvements in electric switches and is concerned with switches of the press-button type suitable for various switching purposes.

5 The principal object of this invention is to provide a press-button switch having a snap action for giving a quick make or a quick break, whereby deterioration of the switch contacts is avoided.

10 A further object is to devise a switch of the character indicated which is economical to produce and of extremely simple construction in spite of the mechanism introduced for the snap action.

15 Yet another object is to construct a switch of the character indicated wherein the closed contacts remain in engagement during the pressing of the knob or button until the moment of release for the snap break action.

20 Finally, an object of the invention is to provide in a press-button switch a combination of a torsional spring and circular action cam surfaces so designed and disposed as to co-operate for the bringing about of the desired snap action at a pre-determined moment 25 of release.

In order to enable the invention to be readily understood a description of one example of construction will be given with reference 30 to the drawings accompanying and forming part of this specification, in which drawings:

Figure 1 is a central vertical section of a switch embodying these improvements, the section being taken on the line A—B of Figure 3.

Figure 2 is an elevation of the internal parts of the switch, these being displayed by removal of one half of the cover or casing which is seen in vertical section on the line C—D of Figure 3.

Figure 3 is a plan of the switch with the cover and press-button removed.

Figure 4 comprises two views, one being an elevation of the upper portion of the switch spindle and the other being a plan thereof.

Figure 5 is an inverted plan of the press-button.

Figure 6 is a sectional elevation of the cen-

tral portion of the movable switch member.

Figure 7 is a developed diagrammatic view of internal teeth within the central portion of the movable switch member.

The switch comprises a cover or casing *a* secured by screwing on a base *b*, a press-button *c* being depressible into the casing *a* with guidance for the depression of the movable switch member *d*. A spindle *e* passing through the perforated centre of the member *d* is detachably secured in the base *b* which is made of porcelain or other insulating material. The means for detachably fixing the spindle *e* and holding it against revolution need not be described as they may be of any appropriate character.

The lower portion of the spindle *e* is of circular cross section and may be of smaller diameter than the upper portion which is formed with flats at diametrically opposite points, the metal being removed to such an extent that the upper portion of the spindle *e* may be said to be of approximately oblong cross section, as will be understood from Figures 3 and 4. At the junction between the upper and lower portions, the spindle *e* is formed with a flange or collar from which project four fingers or star points *f*. If desired, two fingers *f* 180° apart could be used in place of four disposed 90° apart as in Figures 3 and 4. The fingers *f* are bevelled along one side as will be seen clearly from the end view of one of them in the elevation in Figures 1 and 4. The switch member *d* is freely revoluble around the lower portion of the spindle *e* and is pressed upwards against the collar of the star *f* by means of a spring *g*.

The switch member *d* may be moulded as a disc of insulating material having mounted on its upper surface a ring *q* of metal, said ring having radial projections at diametrically opposite points on its periphery and such projections may constitute the contacts of the sliding member *d* for engagement with the fixed contacts hereinafter referred to.

In the centre of the upper surface of the member *d* there is formed or fixed an up-standing hollow cylindrical part *h* which surrounds the upper portion of the spindle *e* and has an internal diameter large enough

for enabling it to slide over the star member *f*. On its interior surface the cylindrical part *h* is formed or fitted with four similar and uniformly spaced teeth *i* which are of triangular or ratchet tooth shape one edge being vertical and the other inclined. If the star member *f* has four points as shown, each of the teeth *i* will engage with one of the points of the star member, which will prevent the teeth *i* and therefore the cylindrical part *h* and movable member *d* from rotating whilst such teeth remain in engagement.

On the exterior of the cylindrical part *h* there are formed or fixed four similar and uniformly spaced projections *k* each of which has its top edge somewhat bevelled, one longitudinal edge vertical and the other longitudinal edge inclined, as seen clearly in Figure 2. The hollow press button *c* which is guided by the casing *a* is pressed into its upward or outward position by a spring *l* coiled around the spindle *e* and reacting between the star member *f* and a central inner portion *n* of the button. On the interior of its cylindrical wall, the press button *c* is formed or fitted with four similar and uniformly spaced projections *m* which, as will be seen from Figure 2, are similar in shape to the projections *k* but are inverted so that their inclined transverse edges come over the inclined top edges of the projections *k* as shown. The spring *l* is adapted for acting torsionally as well as by compression against the button *c* and for this purpose its lower end is engaged with one point of the star member *f* whilst its upper end is engaged in a small hole *o*, Figure 5, formed in the lower end of the central inner portion *n* of the press button *c*. In the normal outward position of the press button *c* shown in the drawing, the spring *l* acting torsionally adjusts the button *c* circularly so that the projections *m* lie immediately over the projections *k* as shown in Figure 2. The central inner portion *n* of the press button extends downwards to the spindle *e* and is formed with a bore *p* which in section or plan, as seen in Figure 5, is of what may be called a double segmental shape. That is to say, the bore *p* is of such a shape as to enable it to slide over the upper portion of the spindle *e* which, in the example illustrated, is of a somewhat oblong cross section, the outer portions of the section of the bore *p* being enlarged so as to permit the part *n* and button *c* to be free to turn through a limited angle relatively to the spindle *e*. This limited turning of the button is performed alternately with and against the torsional action of the spring *l* and it will now be understood how the spindle *e* arrests the turning of the button so that the projections *m* lie directly above the projections *k* when the button *c* is in its outward position as already stated. The limited turning aforesaid is of such amplitude as to en-

able the projections *m* to slip past the projections *k* in circumstances to be explained.

It will be noted from Figure 1 that the cylindrical wall of the button *c* extends downwards below the lower ends of the projections *m* and that the cylindrical part *h* of the member *d* extends upwardly above the upper ends of the projections *k*. As the internal diameter of the button *c* is greater than the external diameter of the cylindrical part *h* to the extent of about the thickness of the projections *m* and *k* it will be understood that there is mutual guidance between the parts *c* and *h* during the sliding movements.

On the base *b* are the upstanding switch contacts *r* and *s*, these contacts being blades fixed by terminal screws *t* and *u* and having upper vertical and parallel portions which may be bent over at the top to engage the projections of the conductor ring *q* above described. Owing to the form and disposition of these spring contacts *r* and *s* it is possible for the member *d* to descend for a certain distance without the breaking of contact between the ring *q* and the contacts *r* and *s* as will be clear from Figure 1.

Assuming the switch to be in the "on" condition as shown in the drawings and that it is desired to put it to the "off" condition, the operation is as follows:—The button *c* is depressed against the compression of the spring *l*. As the projections *m* and *k* are in vertical alignment, the depression of the button *c* will cause also the depression of the member *d*, against the action of the spring *g*. During the first part of the descent of the member *d*, the circuit will not be broken as the contact ring *q* will maintain contact with the blades *r* and *s* as above explained. During this portion of the descent, the vertical edges of the teeth *i* slide against the points of the star *f* so that the member *d* cannot turn. When the member *d* has been depressed so far that the tips of the teeth *i* descend below the star member *f* so that the teeth *i* are no longer engaged by the points of the star *f*, the said member *d* is then free to turn around the spindle *e*. At this moment, and owing to the continued depression of the button *c* against the action of the spring *g*, the bevelled or inclined ends of the projections *m* and *k* will react against one another with a camming action and, seeing that the button *c* cannot turn owing to the engagement of the bore *p* with the upper portion of the spindle *e*, the member *d* will be forced to turn through a small angle due to the projections *k* sliding from beneath the projections *m*. This small turning movement of the member *d* is sufficient to carry the points of the teeth *i* from one side to the other of the star points *f* with which they were in engagement during the descent.

As soon as the projections *k* become disengaged from the projections *m* owing to the camming action aforesaid, the spring *g*, in a

state of compression, is free to elevate the member *d*. As the latter then rises under the pressure of the spring *g*, the inclined edges of the teeth *i* engage the points of the star member *f* so that the member *d* whilst rising to the position in which it is arrested is also caused to turn through a quarter of a revolution owing to the cam action between the teeth *i* and the points of the star. This rising 10 movement and turning of the member *d* is practically instantaneous so that there is a quick break or snap action in the removal of the projections of the ring *g* from contact with the contact blades *r* and *s*. At the end 15 of the rapid turning of the member *d* through a quarter of a revolution, due to the inclined or helical edge of each of the teeth *i* extending around 90°, each of the points of the star *f* will be engaged by the vertical edge 20 of the next following tooth *i* at the end of the movement and the member *d* will be arrested in a position 90° removed from that shown in the drawings. As, at this instant, the button *c* is still depressed, it will be seen 25 that the projections *k* on the cylindrical part *h* of the member *d* will overtake the projections *m* of the button. In order that the coming together of the projections *k* and *m* shall not obstruct this full quarter turn of the 30 member *d*, the longitudinal edges at the meeting sides of such projections are inclined as aforesaid and as seen in Figure 2. Upon now releasing the press button *c*, its work having been finished, the spring *l* returns the same 35 to the outward position and during this ascent of the button the projections *m* will slide past the projections *k* and the said inclined edges of such projections will produce a cam action resulting in a limited turning of the button 40 *c* relatively to the spindle *e* and member *d*. Owing to the ends of the spring *l* being fixedly attached to the star *f* and part *n* of the button *c* respectively, the said spring *l* will be stressed torsionally by the turning of the 45 button under the camming action of the projections *m* and *k*. Thus, immediately the button *c* reaches its uppermost or outermost position so that the projections *m* are clear of the projections *k*, the torque of the spring 50 *l* will turn the button *c* back again to bring the projections *m* immediately over the projections *k* and the original starting condition is restored, excepting that the switch is now in the "off" condition instead of the "on" 55 condition. It will be apparent, without detailed description, that if the button *c* is now again depressed, the member *d* will perform a rapid movement from the "off" position back again to the "on" position shown in 60 the drawings and that for each depression of the button *c* the member *d* will perform such quarter revolution with snap action giving either a make or a break as the case may be. 65

It is to be understood that the details of

construction may be varied without departing from the invention as hereinafter claimed. Thus, for example, the construction and disposition of switch contacts and other details may be modified and changed without affecting the novel and advantageous switching action secured with a press-button switch embodying improvements properly belonging to this invention. 70

I claim:—

1. Press button switch comprising in combination a press button, a rotatably mounted depressible switch member depressible by said button, spaced teeth devices on said member, a fixed abutment member adapted to engage said teeth to prevent rotation of said switch member during depression thereof, said abutment including means to produce pre-determined rotation when said switch member is released, cam devices operative between said button and said member to produce limited rotation of said member at the bottom of the depression, and resilient means operative upon said member to resist depression thereof. 75 80 85 90

2. In a press button switch in which depression of the button depresses a rotatable switch member against the resistance of resilient means, the combination of ratchet-like means operative between said member and a fixed abutment device for preventing rotation of said switch member during depression thereof and for producing rotation during ascent when released by said button, and camming means operative between said button and said member for changing the circular relation between said ratchet-like means and said abutment device at the bottom of the depression. 95 100

3. Press button switch comprising in combination a hollow press button, a fixed spindle, a switch member slidable upon and rotatable about said spindle, guide means operative for guiding said button on said spindle and adapted for permitting limited rotation of said button relatively to said spindle combined abutment and cam devices upon said button and upon said switch member said devices being co-operative for depressing said member during the initial portion of the depression of said button and for subsequently releasing said member for snap action, and snap action mechanism operative upon said member substantially as set forth. 105 110 115

4. Press button switch device comprising in combination a hollow press button, resilient means constantly resisting the depression and the turning in one direction of said button, a fixed guide spindle, means on said spindle co-operative with said button for limiting rotation of said button about said spindle, a movable switch member slidable upon and rotatable about said spindle, tooth devices on said member co-operative with projections on said spindle for preventing 120 125 130

- turning of said member during depression and for producing pre-determined turning of said member during ascent thereof, other resilient means constantly resisting depression of said switch member, and cam devices on said button operative to depress said member and to turn the latter through a limited angle at the bottom of a depression substantially as set forth. 70
5. Press button switch comprising a revolute switch member adapted for depression by said button, fixedly mounted switch contacts adapted for preserving circuit connection with said member during the first part 75
- 15 of said depression movement, snap action mechanism operative for rapidly revolving said member through a pre-determined angle during the final part of said depression, and self-setting abutments on said button and switch member said abutments co-operating to effect depression of said member and finally subsequently releasing said member for the snap action substantially as set forth. 80
- 20 6. Press button switch comprising in combination a hollow press button, a sleeve depending centrally from said button and having a shaped bore, a fixed central spindle having a shaped upper portion adapted for enabling said sleeve to slide longitudinally 85
- 25 over it with ability to turn through a limited angle about said spindle, a star member disposed intermediately along the length of said spindle, a combined compression and torsion spring disposed between said sleeve and said 90
- 30 star and having respective ends connected with said sleeve and said star, a switch member slidable and revolutely mounted on the lower portion of said spindle, a spring coiled 95
- 35 around the lower portion of said spindle and constantly tending to elevate said switch member, spaced ratchet-like teeth on said switch member, normally in engagement with said star but disengageable therefrom 100
- 40 at the bottom of a depression said teeth being 105
- 45 adapted for imparting rectilinear guidance to said switch member during depression and rotational guidance during elevation, cam shaped abutments on said button, and cam shaped abutments on said switch member, said abutments normally lying in vertical alignment and being operative for imparting depression of said button to said switch member and said abutments being 110
- 50 adapted for slipping past one another at the bottom of a depression to release said switch member for ascent in a different circular position and for slipping past one another during subsequent outward movement of said button whereby the first-named spring is torsioned for finally bringing said abutments 115
- 55 into realignment substantially as set forth. 120
- 60 65 7. Press button switch comprising a compressible and rotatable switch member in combination with a rotary step-by-step feed mechanism including means for producing a 125
- 130

CARL GRETER.
